United States Patent Office

Des. 191,229
Patented Aug. 29, 1961

191,229

PAIR OF SPECTACLES

Steve Boxer, 15032 Schoenborn Ave., Sepulveda, Calif.

Filed Nov. 7, 1960, Ser. No. 62,741

Term of patent 14 years

(Cl. D57—1)

I claim:

The ornamental design for a pair of spectacles, as shown.
